Patented Apr. 5, 1966

204,275

POCKET BILLIARD TABLE

David H. Braun, Miami, Fla., assignor to All Tech Industries, Inc., Hialeah, Fla., a corporation of Florida

Filed Aug. 17, 1964, Ser. No. 81,300

Term of patent 14 years

(Cl. D34—3)

FIG. 1

FIG. 2

FIG. 3

FIG. 4

FIG. 5

FIG. 1 is a plan view of the pocket billiard table, showing my new design.

FIG. 2 is a side elevation thereof.

FIG. 3 is a front elevation thereof.

FIG. 4 is a rear elevation thereof.

FIG. 5 is a bottom plan view thereof.

The side not shown is the same as that shown in FIG. 2.

I claim:

The ornamental design of a pocket billiard table, as shown and described.
